UNITED STATES PATENT OFFICE

LOIS HIDE HASHIMOTO, OF SALT LAKE CITY, UTAH

DESIGN FOR AN ARTIFICIAL-FLOWER CLOTHES ORNAMENT

Application filed February 18, 1929. Serial No. 30,122. Term of patent 7 years.

To all whom it may concern:

Be it known that I, LOIS HIDE HASHIMOTO, a citizen of Japan, residing at Salt Lake City, in the county of Salt Lake, State of Utah, have invented a new and original and ornamental Design for Artificial-Flower Clothes Ornaments, of which the following is a specification, reference being made to the accompanying drawing, forming a part thereof.

The figure is a plan view of the artificial flower clothes ornament.

I claim:

The ornamental design for an artificial flower clothes ornament, as shown.

In testimony whereof I have affixed my signature.

LOIS HIDE HASHIMOTO.
